UNITED STATES PATENT OFFICE.

WOODFORD SHANNON, OF LOUISVILLE, KENTUCKY.

SPRING-BED.

1,089,976.

Specification of Letters Patent.

Patented Mar. 10, 1914.

Application filed August 17, 1911. Serial No. 644,495.

To all whom it may concern:

Be it known that I, WOODFORD SHANNON, a citizen of the United States, residing at Louisville, in the county of Jefferson and 5 State of Kentucky, have invented a new and useful Spring-Bed, of which the following is a specification.

My invention relates to spring beds and particularly to those forms with a series of 10 spiral springs.

It has for its object to provide various improvements in the structure of the springs, in the frame support, and in the covering.

15 My invention consists of novel features and parts and combinations of the same which will be more fully set out hereinafter and then pointed out in the claims.

A practical embodiment thereof is shown 20 in the accompanying drawings, in which—

Figure 1 is a plan view; Fig. 2 an end elevation; Figs. 3 and 4, detail views; Fig. 5, a perspective view of the clip; Fig. 6, a detail perspective view of the spring structure; and Fig. 7, a detail view of the means 25 for attaching the cover.

My invention consists first in a novel combination of a tensioning device and the cross-rods of the upper deck construction, and 30 their attachment, to the side frames of a bed bottom support, so as to hold the spring work with relative rigidity against side motion, and at the same time permit practical freedom of compression of the separate 35 rate spirals in such spring work.

My invention further consists in a novel connection between the spirals of the spring work with the supporting bars of the bed bottom support.

40 My invention further consists in a collapsible parallelogram extension attached to side frames of said bed bottom support, swinging therefrom in horizontal planes.

My invention further consists in a novel 45 extension frame, provided with means for detachably fastening the cover of the bed bottom of springs, as shown in Figs. 3 and 4.

As embodied in the drawings, the series 50 of spiral springs 1 are supported in the frame consisting of the side angle bars 11 and the connecting underhung transverse bottom supporting bars 2. These supporting bars are preferably vertically disposed 55 under the springs. The bottom ring of the spiral 1 is connected to a bar 2 by the clip

10 as now about to be described. The clip 10 is placed astride the bar 1, with the open end up and the spirals 1 are then seated on said bars 2 over said clips 10. The rods 18 60 are then placed over the lowermost coils of the spirals 1 and adjacent to the clips 10, whereupon the projecting ends of said clips are bent around said rods by any suitable means in such manner as to effect a tension 65 of said lowermost coils of spirals 1 against both slats 2 and rods 18 of such degree as to hold all of said elements rigidly in place.

In the manufacture of what are commonly known as double deck springs, heretofore 70 the practice has been to provide various devices to prevent the sidewise displacement of the high spirals necessarily employed, such devices being continuous and coterminous with the length and width of the high 75 spiral spring work. Such devices have proven effective to prevent sidewise displacement of the separate spirals, but in practical use there has been found an objectionable side motion of such construction. 80 To prevent such side motion, I have immediately attached the elements 7 by the helical springs 8 and their associated straps to the angle side frames 11. I have also extended the rods 7 but partially across the 85 double deck spring work, connecting the inner ends of such rods 7 by the helical springs 9, all under sufficient tension to withstand the strains tending to produce side motion, but having sufficient elasticity 90 to permit practical freedom of compression of the lower ends of the spirals 1. To further maintain the rods 7 in proper position I employ the longitudinal rods 14, inserting them through the eyes of the rods 7, 95 so that the pressure of the rods 14 upon the eyes of the rods 7 will prevent any torsion of said rods out of their proper planes.

The combination of these rods with the 100 spirals 1 is disclosed in U. S. Letters Patent to me Number 929,333.

The swinging parallelogram extension is attached to the main side angle bars 11 and consists of the bars 6, pivoted to the short 105 arms 5, which are in turn pivoted to the under side of the angle bars 11. By means of the straps connecting with the helicals 8, I hold the side spirals 3 firmly in position upon the flat tops of the side angle 110 bars 11.

I support the covering 12 by the wire

frame 4, supported by connections with the tops of the spirals 1. I fasten it to the frame 13, preferably a light angle bar extending around the bed and supported by extensions from the upper side of the angle bars 11. In this embodiment of my invention I use resilient studs 15 which enter the openings 16 in the frame 13. These openings may be enlarged at their upper ends to hold the studs in place.

I do not limit myself to the exact form in which my invention is herein disclosed further than is indicated in the claims which follow.

15 I claim:

1. A spring bed comprising a plurality of spiral springs, rods passing therethrough adapted to support said springs against lateral displacement, and resilient means for holding said rods under longitudinal tension.

2. A spring bed comprising a plurality of spiral springs, a stiff side frame placed above the bottoms of said springs, rods 25 passing through said springs and connected with said side frame adapted to support said springs against lateral displacement, and resilient means for holding said rods under longitudinal tension.

3. A spiral spring, a supporting member bearing at two opposite points of the face of a ring of said spring and being narrower than the diameter of said ring, a key mem-

ber binding said ring on the face opposite to that supported by the said supporting member and at points between the points of support; and a clip straddling said supporting member and bent over said key member on opposite sides of said supporting member at points within said ring.

4. A spring bed comprising a series of springs, an outside support on the upper surface thereof, an outside lower support, an extension frame therefrom approximately parallel to said upper support, and 45 a cover drawn over said upper frame and fastened to said lower extension.

5. A spring bed comprising a series of springs, an outside support on the upper surface thereof, an outside lower support, 50 an extension frame therefrom provided with holes, and a cover provided with resilient studs and drawn over said upper frame and fastened to said lower extension by said studs.

6. A spring bed comprising a rigid bed bottom support, a bed bottom of springs built thereupon, and a swinging parallelogram extension from said bed bottom support adapted to change the width of said 60 bed bottom support.

WOODFORD SHANNON.
